1 Claim 10

ABSTRACT OF THE DISCLOSURE

The blast door is part of a missile launching system having a magazine, storing missiles in a vertical position, and provided with a cover or base ring assembly on which is mounted a launcher guide arm receiving missiles from the magazine. The door opens and closes to permit the passage of the missiles from the magazine to the guide arm. It is provided with safety devices to prevent firing of the missile until the door is closed and sealed. It prevents the exhaust gases, from the missile, entering the magazine and carries a spanner rail extension for missile travel that bridges the rail of the magazine and the rail of the guide arm.

CROSS REFERENCE TO RELATED APPLICATIONS

This application for a blast door for a missile launching system is a component part of application, Serial No. 493,283, filed Oct. 5, 1965, now U.S. Patent No. 3,367,234, for Guided Missile Launching System.

BACKGROUND OF THE INVENTION

Field of the invention

This invention relates to that type of apparatus known as closures and more particularly to a hatch or door, automatic in operation, capable of being sealed against the entrance of gases and supporting component parts which function to assist the passage of articles through the portals of the door.

Description of prior art

Heretofore in missile launching systems the magazine is separated from the launcher guide arm by a considerable distance, and the door between the two is not limited by space and necessary structure. In combining the magazine and launching platform on which the guide arm is mounted a problem of a suitable and effective blast door arose.

SUMMARY OF THE INVENTION

The blast door of the present invention must fit between the top of the magazine and the guide arm. It is a rectangular door, mounted on a pivot that has vertical movement through a limited distance, then rotation in a horizontal plane. It carries a spanner rail to bridge the magazine rail and the rail of the guide arm to give the missile a continuous rail. Its operating mechanism has cooperating safety features to prevent movement of the missile without the door being fully opened and means preventing firing of the missile without the door being shut and latched.

An object of the present invention is to provide a door leading from a magazine where the missiles are stored in vertical positions to the launcher guide arm of the missile system which is first moved through a vertical displacement and later swung in a horizontal plane to uncover the opening through which the missiles must pass.

Another object is to provide a blast door that will shelter the magazine from the blast of the fired missile and which will be capable of being sealed against the entrance of any exhaust gases.

2

It is another object of the present invention to provide a door capable of carrying a section of rail spanning a gap between the rail of the magazine and the rail of the launcher guide arm, and to be of such precision construction that when in open position the rail will exactly fit the gap between the other missile carrying rails.

It is still a further object of the present invention to provide a door which carries a safety mechanism which prevents the hoisting of the missile until the door is in locked-open position.

DESCRIPTION OF THE DRAWINGS

The invention is illustrated in the accompanying drawings, in which:

FIG. 1 is a side elevation of the launcher guide arm and showing part of the magazine in section;

FIG. 2 is a top plan view of the door mounted on the base ring of the magazine;

FIG. 3 is a mechanical and hydraulic schematic view of the door and operating parts shown in the closing cycle.

Referring to the drawings in detail wherein like parts are referred to by like numbers throughout the several views. FIG. 1 shows a portion of the magazine 11 in section, the top of the magazine being covered by a plate known as the base ring 12. This base ring 12 is formed with an opening 13 through which the missile passes from the magazine 11 to the launcher guide arm 14. The missile travels by engagement of a forward shoe 15 and an aft shoe 16 which move in, first, the magazine (fixed) rail 17, and, later, in the guide arm rail 18. These rails are separated in order that the guide arm may be elevated and trained for firing, and the gap is closed by a spanner rail 19 which is attached to the blast door 21.

The blast door is a rectangular metal door mounted at one corner to pivot post 22 and supports the spanner rail 19 along one side. It also has a projecting stud 23 located in the top of the door for positioning the door exactly with regard to the elevating mechanism. This spud mates with a socket 24 in the elevation positioner 25. When the door is in closed position the spanner rail 19 is housed in housing 26 (FIG. 1) which is carried on the base ring. The rim of the door is downturned and formed with a groove 27 (FIG. 3) adapted to engage a sealing resilient ring 28 carried by the base ring.

45 The pivot post 22, supporting the blast door, is mounted in bearing structure 29 located in the base ring and is formed with a camming groove 31. This groove rides over the projecting cam 32 and because of its shape causes the door to first rise one and one-quarter inches before swinging in a horizontal plane. Rotation is imparted to the pivot post through a gear 33, carried by the post and in mesh with a rack 34 connecting pistons 35 and 36.

55 The operation of the door is hereafter briefly described, with no intention of tracing the hydraulic pressure through the valves and the actuating pistons.

Opening cycle

Energizing a solenoid 42 located in a solenoid housing 41 initiates a series of hydraulic and mechanical actions that open the blast door. With this energization, a rod 44 is moved to the left and a valve 51 moves to permit pressure from a system 62 through a valve 61 to enter the valve 51 and from there to latch valves 57 and 58. The hydraulic pressure shifts both of these valves against spring action. The movement of the valves 57 and 58 ports the pressure to vertical travel valve 52 and rotation start valve 55. The pressure shifts a valve 52 against spring pressure and passes to the underside of piston 22a at 45. This raises the blast door through its initial vertical displacement about 1 1/4 inches.

As the piston 22a rises, it raises the plunger of valve 55 and this movement of 55 passes the hydraulic pressure to rotational directional valve 56 which acting against spring pressure passes the pressure of the hydraulic fluid to the door rotation piston 36. Movement of the rack 34 causes rotation of the gear 33 and its attached piston 22. This rotation continues rotating the blast door through an approximate angle of 90° to bring the stud 23 to a specific location under the socket 24 of the elevation positioner 25.

As the rack 34 moves to the left, hydraulic fluid is ported out of the cylinder at 47, through valve 56 to the rotation metering valve 53. Rotation of the blast door causes the linear section of the cam plate 48 to change position with respect to the plunger valve 53. This valve 53 is moved to permit an increasing amount of fluid from valve 51. The hydraulic fluid passes through 53 and 54 to a tank. The valves 53 and 54 function to control the rate of blast door movement.

The cam groove 31 regulates the vertical movement of the blast door. After rotation of the door through 90° a latch on the blast door engages the end of a Bowden wire 63 and moves the valve 64 which is interlocked with the hoisting mechanism and makes certain that the hoisting mechanism cannot be operated until the blast door is in open, locked position. With the door open and latched, the spanner rail is in position bridging the fixed rail of the magazine and the retractable rail of the guide arm to permit travel of the missile from the magazine to the launcher guide arm.

Closing cycle

The blast door is prepared for closing by withdrawing the elevation positioner socket 24 from the stud 23. This withdrawal actuates the solenoid 43 and starts the closing cycle.

Hydraulic pressure from the control valve 61 passes through 51 to open door latch valve 59 thus unlatching the blast door. As the valve shifts the pressure is ported to valve 56 and to the piston 22 at the point 46. The valve 56 is shifted and the fluid pressure is directed to the cylinder 38 at 47 and acts on the piston 35 to push the rack 34 towards the right. The movement of the rack rotates the gear 33 and rotates the blast door. Rotation of the blast door brings the door to closing position, and fluid pressure against the shoulder entering at 46 to move the piston vertically to closed position. With the door closed, valves 57 and 58 are actuated to latch the door in closed position. With the latching of the door, indicators (not

shown) indicate that the door is in closed position and the missile may be fired.

Obviously many modifications and variations of the present invention are possible in the light of the above teachings.

What is claimed is:

1. In a missile launching system having a magazine, storing missiles in vertical positions and having a base ring covering the magazine and supporting a launcher guide arm above these missiles, the base ring having an opening for passing the missiles from the magazine to the launcher guide arm, the magazine having spaced, in-line missile guide rails and housing a missile hoisting means, a blast door for the opening comprising:
  - 10 a metal covering formed with down turned edges, said covering being mounted on a pivoted post supported in bearings in the base ring;
  - 15 means carried on the surface of the door for exactly positioning the door when open;
  - 20 means hydraulically operated for latching the door in closed position;
  - 25 means carried by the door adapted to be positioned when the door is swung to open position between a missile retractable guide rail of the magazine and a missile guide rail of the launcher guide arm to provide uninterrupted guidance for the missile from the magazine to the guide arm;
  - 30 means for latching the door in open position;
  - 35 a Bowden wire supported by the magazine having one end engaged by said open position latch means upon movement of the blast door to fully open position; and
  - 40 a valve normally preventing operation of the missile hoisting means, said valve being mounted in the magazine and in contact with the free end of the Bowden wire, whereby movement of the wire through contact with the open position latch means will actuate the valve to permit actuation of the hoisting means.
